Primary Examiner — Joseph Kukella*Assistant Examiner* — Darryl J Dardenne(74) *Attorney, Agent, or Firm* — Reising Ethington P.C.**CLAIM**

The ornamental design for a beverage generating kiosk, as shown and described.

DESCRIPTION

FIG. 1 is a perspective view of an embodiment of a beverage generating kiosk showing our design;

FIG. 2 is a front elevational view of the embodiment of the beverage generating kiosk of FIG. 1.

FIG. 3 is a left side elevational view of the embodiment of the beverage generating kiosk of FIG. 1.

FIG. 4 is a right side elevational view of the embodiment of the beverage generating kiosk of FIG. 1.

FIG. 5 is a rear elevational view of the embodiment of the beverage generating kiosk of FIG. 1.

FIG. 6 is a top plan view of the embodiment of the beverage generating kiosk of FIG. 1; and,

FIG. 7 is a bottom plan view of the embodiment of the beverage generating kiosk of FIG. 1.

In the drawings, the oblique lines represent transparent or translucent surfaces such as the surfaces of hoppers of the beverage generating kiosk.
